DRY SHAVING DEVICE

Raymond Knapp, Long Island City, N. Y., assignor
to Knapp-Monarch Company, St. Louis, Mo., a
corporation of Missouri

Application April 11, 1938, Serial No. 201,373

1 Claim. (Cl. 30—43)

My invention relates to hair clippers and particularly to a type of hair clipper designed to cut hair extremely close to the skin and commonly termed a dry shaver. Among the objects of my invention is the provision of a new and improved dry shaver which is capable of producing a clean, smooth shave after one operation over the skin.

Another object is the provision of a new and improved dry shaver which has a combination of perforations supplied in a cutting head adapted to give a rough shave followed immediately by a smooth finish shave as the instrument is passed once over the skin.

Still another object is the provision of a new and improved dry shaver capable of giving both a rough and finished shave as a result of one application of the machine which is accomplished by supplying a cutting head provided with a variety of perforations through which the hair may project which differ either in dimension or in relative position upon the cutting head so that hair which may not be completely cut off close to the skin in one set of perforations may be properly cut in a succeeding set of perforations.

Still a further object is the provision of a dry shaver supplied with a cutting head having a curved outline with perforations completely surrounding the curved portion so that as the instrument is passed over the skin upon which a beard may grow close to the skin or slanting in various directions the perforations will be so positioned as to permit all of the beard stubs to enter the cutting head and be cut off therein close to the skin.

A further object is the provision of a dry shaver supplied with a rounded skin plate so that there may be perfect comfort for the user and one which due to the employment of operating parts of a greater simplicity is relatively inexpensive to manufacture so as to be within reach of the average person of modern means.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a fragmentary longitudinal section of a dry shaver showing a cutting head in position.

Figure 2 is an end view of the cutting head

partially in section taken on the line 2—2 of Figure 1.

Figure 3 is a side view of the cutting head partially in section taken on the line 3—3 of Figure 1.

Figure 4 is a cross section of the cutting head taken on the line 4—4 of Figure 3.

Figure 5 is a perspective view of the cutting edge showing the cutter partially withdrawn.

Figure 6 is a fragmentary longitudinal section of a dry shaver body showing a modified form of my cutting head in position.

Figure 7 is a side view of the modified form of a cutting head partially in section taken on the line 7—7 of Figure 6.

Figure 8 is a cross section of the cutting head taken on the line 8—8 of Figure 7.

Figure 9 is a bottom view of a modified form of a cutting head taken on the line 9—9 of Figure 7.

Figure 10 is a cross section of still another form of my device.

In the construction of clipping machines or dry shavers which are designed to shave the skin without the use of lather there are structural limitations which necessitate careful engineering in order to produce a machine which will effect a close shave comparable to that made possible by the well known old fashioned straight razor. The use of an ordinary razor when it does not completely cut the beard stub close to the skin frequently results in cutting sharp points on the beard. Therefore, even in the use of a straight razor it is almost always necessary to shave twice over the face in order that short and frequently sharp stubs of beard may be completely removed. Similarly in dry shavers heretofore devised it has nearly always been necessary to shave two or three times over the bearded skin and then frequently to shave at a very slow pace in order to produce the requisite close shave, which is the only shave that spells real comfort for a shaver.

The invention herein described employs a rounded skin plate forming a cutting edge which produces a comfortable feeling when passed over the skin and which is provided with a novel arrangement of perforations functioning as teeth at the shearing area of the cutting head. The perforations are spaced in rows and alternate with each other so that the cutting edge of each successive perforation is displaced slightly in a lateral direction from the edge of the perforation next adjacent. By reason of perforations being spaced around the curved sides of the skin plate

the hair of a beard which lies at an angular direction close to the skin can be caused to initially enter at least some of the perforations on the side of the skin plate as the cutting head is passed over the skin. These diagonal lying hairs will then receive a rough cut by the first perforations which is followed immediately by a fine or close cut performed by a set of perforations located at the crown of the curved skin plate as the skin is folded around the rounded cutter. There are provided a great number of perforations lying in a direction to pick up the beard regardless of its direction and by this means in passing the skin plate once over the skin both a rough cut and finished cut is provided which results in a quick smooth shave.

In the embodiment chosen to illustrate my invention there is shown a dry shaver having a body A provided with a cutting head B inserted at the end. In the body there is provided an actuating arm 10 suitably mounted upon a pivot 12 and driven by some power element not shown. The arm 10 is curved around so as to enter the cutting head B when it is in place in the body. The body itself includes an end piece 14 secured by some convenient means to handle portions 16 and 18 and provided with a retaining means such as screws 20 for holding the cutting head in place.

The cutting head itself in the embodiment shown consists of a stamping having flat parallel sides 24 joined by a semi-circular curved arc 26. The flat sides 24 are spread apart by a spacer 28 and are secured in place upon the spacer by rivets 30. Flanges 32 are formed at the ends of the stamping to give strength and rigidity to the member. Where desired a slight depression may be supplied at the points 34 in order that the cutting head may be conveniently clamped within the body and readily removed therefrom.

The spacer itself has provided therein a deep slot 36 within which operating arm 10 is inserted for driving the moving element of the cutting head. Also in the spacer are provided a pair of passages 38 one at each end which are capped by sleeves 40. A square groove 41 extends from end to end.

Each sleeve in turn has a central aperture 42 and within the aperture there is positioned a rod 44 having a knob 46 at the right hand end as viewed in Figures 3 and 4. A coiled spring 48 urges the rod toward the right and it is prevented from being pushed completely through the aperture 42 by means of a fin 50 pinched at the end opposite the knob 46.

The stamping 24 forms an outer shear plate and since the arc 26 forming a part of the shear plate actually moves in contact with the skin, it can aptly be termed a skin plate. The skin plate therefor is provided with a row of slots 52 at the crown of the arc which are designed to make the finished cut or close shave as the plate is passed over the bearded skin. Symmetrically disposed at either side of the crown slots there is provided a series of rows 54, 56, 58, etc., of perforations with the perforations in each alternated or staggered with relation to the perforations in each adjacent row, it being also apparent that the perforations in rows 54 are staggered with relation to the crown slots. It should be borne in mind however that this staggered arrangement is merely a means of placing the lateral shearing edges of the perforations in staggered relation to each other so that as the plate is

passed over the skin successive shearing edges will be in a position slightly at one side or another of the shearing edge immediately preceding it. By this arrangement the entire beard can be cut as the plate is passed once over the skin.

The perforations comprising the rows 54, 56 and 58 may be made greater in diameter than the widths of the slots 52. By arrangement of this sort, the cutting edges of the perforations are necessarily displaced laterally to some extent from the cutting edges of the slots 52. In addition, by making the perforations larger, they are capable of receiving more readily the stubs of a coarse beard in order to make an initial rough cut and with the beard once rough cut, the slots 52 can be conveniently employed to make a smooth close finish cut.

By spacing the rows 54, 56 and 58 of perforations around the rounded side of the skin plate 26, they are adapted to receive the ends of hair which lie at an angle to the skin, particularly when pressure on the plate depresses the skin causing it to surround the plate in a slight fold. As the plate is passed over a skin having a beard growth of this sort, the ends very readily project straight into the perforations where they can be sheared off.

A somewhat cylindrical cutter 60 is supplied for the cutting head located at the inner side of the skin plate 26. The cutter is formed by milling a plurality of transverse slots 62 across one side of the cutter producing a series of teeth 64. The slots are made of ample depth so that the teeth 64 thus formed completely contact the edges of all of the perforations in the skin plate.

Another feature of the cutter is the provision of a central aperture 66 drilled slightly eccentric from the center line of the cutter so as to make the teeth 64 hollow and vary the thickness thereof from a minimum at the crown 68 to a maximum at the spring line 70 forming teeth which have the shape of an arc. Teeth formed in this manner have the advantage of being light in weight and still rigid in construction.

At the side of the cutter opposite from the teeth there is provided a flat 72 and in the flat are a pair of depressions 74 one at each end adapted to receive the knob 46 which is spring pressed thereinto by the coil spring 48. In this manner the cutter 60 is pressed into shearing contact with the inside of the skin plate and is prevented from rotating with respect thereto. At the center of the flat there is provided a transverse recess 76 adapted to the reception of a rounded end 78 of the arm 10. As the arm reciprocates back and forth the rounded end 78 being forced against the walls of the recess 76 rapidly reciprocates the cutter back and forth within the skin plate.

In a modified form of my device there is shown a dry shaver having a body A' which is provided with a cutting head B' mounted thereon. The body is provided customarily with an actuating arm 10' suitably mounted upon a pivot 12' and driven by the usual power element, not shown. The body is provided as is customary with handle portions 16' and 18', these handle portions forming a hollow cavity 80 within the body. There is also mounted in the body a spring clip 82 having an arm 84 extending upward and toward the right in a position to contact with the cutter element B.

The cutter element itself in the embodiment shown is made of a single stamping having paral-

lel sides 86 which are joined by an arcuate portion 88, the arcuate portion being provided with a plurality of rows of perforations 90. Each of the ends of the stamping are provided with a flange 92 which gives strength and rigidity to the device.

Parallel sides 86 are held apart in parallel arrangement by a spreader 94 located on the inside between them. On the outside of each of said parallel sides there is positioned a plate 96 which is riveted to the parallel sides and the spreader by a series of rivets 98, thus holding the supporting part of the cutting head in rugged and rigid assembly. The outer plate 96 in each case is provided with an elongated groove 99 which when the cutter head is inserted in the body portion engages the resilient clip 84 to releasably hold the cutting head in position in the body.

In this form of my device similar to the first form described there is shown a deep slot 100 in the spreader through which an end 102 of the actuating arm projects in order to be operatively connected with the cutting head.

There is provided also a movable cutter 104 which is equipped with a plurality of semi-circular hollow teeth 106. The rear section of the cutter, directly behind the semi-circular teeth is somewhat rectangular in cross section and substantially fills the space between the parallel sides not filled by the spreader 94. The cutter has formed therein a depression 108 for the reception and engagement with the end 102 of the actuating arm 10.

The cutter by reason of having a base portion 35 rectangular in cross section is adapted to fit snugly within the outer end of the cutting element and adds rigidity to it particularly since the semi-circular teeth 106 completely mesh with the entire inside surface of the arcuate portion.

40 In order to be sure that the cutter teeth ride snugly upon the inside surface of the arcuate portion, there is provided a pair of spring pressed rods 110 lying within passages 111 and urged into position against the cutter blade by a helical spring 112. The springs in turn bear against sleeves 114 threaded into the passages, the spring pressed rods being prevented from being pushed completely through the sleeve by means of fins 116 pinched upon them at the outer ends.

50 In a cutting head of this sort, the entire space inside the walls forming the skin plate is substantially filled with the spreader and cutter forming in effect, a solid metallic core, part of which is stationarily riveted thereto and part of 55 which comprises the rapidly reciprocating cutter. A construction of this sort makes a relatively heavy, rigid cutting head especially in a construction wherein relatively thin stamping material is used in order to form the outer walls.

60 Figure 10 shows still a further modification of a cutter head, the outside walls of which are built up of a stamping. This stamping is formed in a manner similar to members described in the other modifications herein described in that it is composed of a metallic sheet having parallel side portions 120, a pair of opposite and angularly disposed flat side portions 122 joined by an arc 124

of the same material which exceeds a measurement of 180 degrees in curvature. The arc as heretofore described is perforated, forming thereby substantially a net work of holes 126 through which the hair stubs project when the device 5 is used for shaving.

Between the parallel side portions 120 there is interposed a spreader 128 and on the outside of these same sides there is a pair of plates 130 with all of the parts held together by means of a rivet 10 132. The outer plates have in them the customary groove or depression 99' engageable with the clip 84.

In this modification there is provided a cutter of particular design having a shank or base portion 134 primarily trapezoidal in cross section so as to fit snugly within the somewhat bulbous end of the cutting element and, as previously described, substantially filling the space within the cutting head. The cutter blade is provided also 20 with hollow arcuate teeth 136 of uniform breadth and thickness cooperable with the arcuate portion 124 of the stamping to form a shear plate.

Here again there is provided a cutting head of extremely rigid construction which is relatively 25 heavy and which is additionally braced by the sloping sides confining between them, the somewhat trapezoidal base of the cutting element thereby assisting materially in holding the teeth of the cutting blade in shearing position.

There has been provided therefor a round smooth operating cutting head for a dry shaver so provided with a variety of shearing perforations that by a single application to the bearded skin, a comfortable close shave can be secured.

Some changes may be made in the construction and arrangement of the parts of my device without departing from the real spirit and purpose of my invention, and it is my intention to cover by my claim any modified forms of structure or use 40 of mechanical equivalents which may be reasonably included within its scope.

I claim as my invention:

In a shaver, a cutting head including an outer skin plate comprising a perforated stamping having flat sides joined by a semi-circular arc of the material of uniform thickness, said arc having a series of narrow finish cut slots at the crown for the admission of hair stubs and a plurality of rows of rough cut holes on each side of the crown 50 separated from the slots and larger in diameter than the width of said slots, the perforations in each row being spaced alternately with respect to the perforations in adjacent rows and adapted to admit the ends of hair stubs as the plate is 55 passed over the skin, the portion of the skin plate between the holes and the slots being adapted to temporarily depress the hair stubs and then snap said stubs into the finish slots, an inner cutting member cooperable with the perforations to 60 progressively shorten the hair stubs as the cutting head is passed over the skin and resilient means in said cutting head urged against the cutting member to press the cutting portion only of said member into shearing position.
